US00D694263S

(12) **United States Design Patent**
Simmons et al.

(10) **Patent No.:** US D694,263 S
(45) **Date of Patent:** ** Nov. 26, 2013

(54) **DISPLAY SCREEN OR PORTION THEREOF
WITH GRAPHICAL USER INTERFACE**

(71) Applicant: **Apple Inc.**, Cupertino, CA (US)

(72) Inventors: **Dan Simmons**, San Francisco, CA (US);
Gregg Suzuki, Daly City, CA (US)

(73) Assignee: **Apple Inc.**, Cupertino, CA (US)

(**) Term: **14 Years**

(21) Appl. No.: **29/446,688**

(22) Filed: **Feb. 26, 2013**

Related U.S. Application Data

(63) Continuation of application No. 29/392,466, filed on May 20, 2011, now Pat. No. Des. 677,685.

(57) **CLAIM**

The ornamental design for a display screen or portion thereof with graphical user interface, as shown and described.

DESCRIPTION

The FIGURE is a front view of a display screen or portion thereof with graphical user interface showing our new design. The broken lines around the FIGURE showing a display screen or portion thereof form no part of the claimed design.
